CLASP FASTENER OR SIMILAR ARTICLE

Jon Hedu, Watertown, Conn., assignor to
Watertown Manufacturing Company

Filed Sept. 27, 1963, Ser. No. 76,754

Term of patent 14 years

(Cl. D17—3)

FIG. 1 is a perspective view of a first embodiment of a clasp fastener or similar article in which the generally flat male member is slightly bowed, and both members are provided with elongated apertures through their extreme opposite ends for attachment to a garment, belt or other article. The elongated aperture on the female member is located on a flat portion extending therefrom.

FIG. 2 is a front elevational view of the embodiment of FIG. 1;

FIG. 3 is a plan view of the embodiment of FIG. 1;

FIG. 4 is a perspective view of a second embodiment of a clasp fastener or similar article in which the male member is flat and the female member has its major face opposite to its open face cut out to provide a forwardly inclined tongue. A flat portion extends from the outermost end of the female member; and the extreme opposite ends of both male and female members are provided with bores adapted to receive pintle members.

FIG. 5 is a front elevational view of the embodiment of FIG. 4;

FIG. 6 is a plan view of the embodiment of FIG. 4;

FIG. 7 is a sectional view taken along line 7-7 in FIG. 5;

FIG. 8 is a perspective view of a third embodiment of a clasp fastener or similar article in which the shoulder of the male member is surrounded on three sides by a U-shaped slit. The extreme opposite ends of both mem-

bers are provided with integral elongated pins to facilitate attachment to a garment, a suitable fitting or other article.

FIG. 9 is a front elevational view of the embodiment of FIG. 8; and

FIG. 10 is a plan view of the embodiment of FIG. 8.

The dominant features of the various illustrated embodiments reside in a generally flat male member provided with a tapered shoulder which is spaced from the edges thereof; and a female member which is a hollow rectangular prism provided with centrally located openings in one end and in a major face thereof.

I claim:

The ornamental design for a clasp fastener or similar article, substantially as shown and described.
